AWNING

Jonathan W. King, Jr., Niles, Ohio

Application June 17, 1952, Serial No. 293,897

8 Claims. (Cl. 160—62)

1

My invention relates to awnings, more particularly to awnings formed of metal or the like, and the principal object of my invention is to provide new and improved awnings of the character described.

Many prior attempts have been made to provide an awning structure formed of metal or the like which would possess advantages not possessed by the common canvas awning. To date, however, the metal awnings which have had the widest commercial success fail to provide for adjustment of the awning to satisfactorily vary light and ventilation passed thereby. Since an adjustable metal awning is very desirable, it is apparent that the failure of adjustable metal awnings of the prior art to achieve commercial success may be interpreted as a failure to provide suitable structure.

My invention provides an awning which is preferably formed of metal and since it is not affected by weather, it may be left permanently in place and used throughout the year. The awning may be manufactured and distributed inexpensively since, with my invention, it is not necessary to stock a large number of different parts in order to accommodate various sizes of windows. My improved awning may be adjusted to provide conventional awning protection for a window, and may be adjusted to provide free entrance of air and light thereto, or adjusted to any intermediate position therebetween.

These and other advantages will become apparent from the description which follows and from the drawings forming a part of this application, and in these drawings:

Figure 1 is a side elevational view illustrating an embodiment of my improved awning in extended position.

Figure 2 is a view similar to Figure 1 but showing parts in contracted position.

Figure 3 is a fragmentary view similar to Figures 1 and 2 but showing parts in an intermediate position.

Figure 4 is a fragmentary, exploded perspective view illustrating a detail of construction, certain parts being removed in the interest of clarity.

Figure 5 is an enlarged, fragmentary, exploded perspective view of the preferred embodiment of a detail of my invention, and

Figure 6 is a fragmentary, side elevational view illustrating my invention applied to a vertical structure such as a porch end drop, certain parts being broken away to better illustrate con-

2

struction and certain parts being shown in another position by dot-dash lines.

Referring now to the drawings, and particularly to Figures 1 and 4, it will be seen that my improved awning comprises a bracket 10 formed of legs 11 and 12 adapted to be secured to a supporting surface such as a window frame 13. For ordinary purposes, two brackets 10 will be employed, one at each side of the window frame. 10 It is to be understood, however, that intermediate brackets could be employed in the event of an extremely long awning, and these intermediate brackets, although perhaps slightly different in form, would act in manner similar to the brackets to be described.

Since the two brackets ordinarily used in my awning construction are similar in structure and function, only one is herein shown and described, it being understood that a description of one is 20 equally applicable to the other.

As previously mentioned, the bracket 10 comprises legs 11 and 12, and these legs are presently preferably formed of metal and are of angular cross-section. The leg 11 is formed with 25 a generally laterally-extending arcuate portion 14 which is adapted to be pivotally secured to the leg 12 at 15 (the purpose of this construction will later be described). Each leg provides a foot-like portion 18 adapted to lie against the supporting surface 13, and screws 19 may pass through apertures in respective feet to secure the bracket to the supporting surface.

As best seen in Figures 1 and 3, interconnected links 16 forming lazy tongs are pivotally secured to the leg 12 at points 17. An outer pivot 20 of each of the links forming the lazy tong is adapted to pivotally carry a slat 21 and an extension of the leg 12 of the bracket 10 is adapted to provide a pivot 22 aligned with the pivots 20. The pivot 22 of the leg 12 pivotally supports a master slat 23 which cooperates with the slats 21 to form the window protective awning surface.

Each of the slats 21 is formed to provide a downwardly turned leading edge and an upwardly turned trailing edge, and each slat has secured thereto a laterally projecting elongated finger 24 which extends beyond the trailing edge of the slats. In the embodiments disclosed in Figures 1, 2, 3 and 6, each finger may have a portion thereof bent over so as to lie in the plane of the slat and this bent-over portion may be spot welded or otherwise secured to the slat.

Each finger 24 is apertured at a position intermediate the ends thereof for securing the finger and its attached slat to a respective pivot

20, and the free end of each finger 24 is apertured for a purpose later to appear. Master slat 23 is formed similar to slats 21; however, the trailing edge of slat 23 extends beyond its pivot 22. The finger 25 which secures slat 23 to the leg 12 is similar to the fingers 24 with the exception that it does not project beyond the pivot 22 and it additionally provides a tab for pivotal connection with a curved link 26.

As best shown in Figures 1, 2 and 3, each of the pivots 20, with the exception of the lowermost pivot, have one end of a link 27 secured thereto. The free ends of links 27 are pivotally secured to respective adjoining free ends of fingers 24. Secured to the pivot 22 is a link 28 similar in all respects to links 27, and the free end of link 28 is pivotally connected to the adjoining finger 24 as previously described.

The curved link 26, as mentioned above, has one end thereof pivotally connected to a tab carried by the finger 25. The free end of the link 26 is pivotally secured to one of the lazy tong links at 29.

Secured to the leg 11 of the bracket 10 is a stationary slat 30 which has an edge 31 formed in the same manner as the leading edges of the movable slats. The opposite edge of the slat 30 may extend to the frame 13 and any suitable means may be employed to provide a weather tight seal therebetween.

As best shown in Figure 4, the slat 30 is presently secured to the legs 11 of the brackets 10 by the following means: One or more tabs 32, each secured to the slat 30 by any desirable means, may extend laterally therefrom. Each tab is provided with an aperture 33 and each leg 11 is provided with a notch 34 which aligns with apertures 33 when slat 30 lies along the legs 11 as shown in Figures 1, 2 and 3. At assembly, a rod 35 may be passed through the apertures 33, the rod extending across the spaced legs 11 and resting in the notches 34. Thus it is apparent that the slat 30 may be easily secured to the legs 11 regardless of the spacing between the brackets simply by inserting the rod 35 through the aligned apertures and notches.

Referring now to Figure 1, it will be seen that each slat has interlocking engagement with adjoining slats to limit extension of the lazy tong 16 to the position shown. This interlocking engagement also provides a weather tight joint so that a window to which the awning is secured will be completely protected from the elements.

The means presently employed to actuate my improved awning is herein shown to comprise a cord 36 secured to the lowermost pivot 20. The cord may be trained over a pulley 37 in conventional manner to provide a depending portion which may be pulled downwardly to actuate the awning.

As best shown in Figure 3, pulling on the cord 36 will cause the lazy tong links to collapse toward the support 10. As the links collapse and the pivots 20 move toward each other and toward the pivot 22, the links 27, 28 which are secured to the fingers 24 will cause the slats 21 to rotate simultaneously about respective pivots. Slat 23 is rotated simultaneously with the slats 21 by action of the curved link 26. Thus it will be seen that the awning may be partially raised to admit more light to the window but it will still offer some protection from the elements and from the hot overhead sun. Furthermore, as illustrated in Figure 2, my novel awning may be raised completely to provide free access of light and ventilation to the window in the manner of the conventional canvas awning.

As mentioned heretofore, the leg 11 of the bracket 10 is pivoted to the leg 12 at 15. This construction provides for varying the angle of the extended awning with respect to the window frame.

The means contemplated for securing the stationary slat 30 to brackets 10 to provide for varying the spacing between the brackets has been described and illustrated in Figure 4. However, with the finger construction illustrated in Figures 1, 2, 3 and 6, each awning would require the slats thereof to be custom made to provide the correct spacing between the fingers.

Figure 5 illustrates a finger construction which may be moved longitudinally of the slat to provide whatever spacing is required. As clearly shown in the drawing, the finger comprises a lower portion 38 and an upper portion 39 adapted to be clamped about a slat. Ends 40 and 40 respectively of the upper and lower portions are formed to interlock with each other and the opposite ends of both portions are adapted to be secured together by fastening means 41. The leading edge of a respective slat 21 is adapted to seat in a groove 40a in the lower portion 38 and the trailing edge of such slat is adapted to seat in a groove 40b in the upper portion 39. Although only the construction of finger 24 is shown in Figure 5, it will be apparent that finger 25 is also formed in a similar manner.

Figure 6 illustrates my invention applied to a drop awning for closing off one end of a porch or the like. Brackets 42, having depending track portions 43, may be spaced apart from each other and secured between the ceiling 44 and the floor 45. In this construction, the lazy tongs are not pivotally secured to the brackets but carry rollers 46 which ride in the tracks 43. The operating cords 47 may be secured to the lowermost intermediate pivots of the lazy tongs, and it will be evident from the previous description that the slats will be moved to the dot-dash position shown as the cord is pulled up.

In view of the foregoing it will be apparent to those skilled in the art that I have accomplished at least the principal object of my invention and it will also be apparent to those skilled in the art that the embodiments herein described may be variously changed and modified, without departing from the spirit of the invention; and that the invention is capable of uses and has advantages not herein specifically described, hence it will be appreciated that the herein disclosed embodiments are illustrative only, and that my invention is not limited thereto.

I claim:

1. A foldable slat-type awning, comprising a series of slats, each having a tail piece extending transversely therefrom, a pantograph support for said slats comprising a series of crossed pivotally connected links to form an extensible and contractile lazy tongs, the pivoted ends of said links at one side of said lazy tongs being pivotally connected to respective ones of said tail pieces, and a plurality of link members respectively pivotally connected at one end to the aforesaid pivotal connections between the slat tail pieces and lazy tongs, and at their opposite ends to adjoining tail pieces, whereby said slats are rotatable in opposite directions on their pivotal connection to said lazy tongs respectively by extension and contraction of the latter, movement of said lazy tongs to an extended position extending said slats to trans-

versely, substantially edge-to-edge relation, and movement of said lazy tongs to contracted position collapsing said slats into substantially parallel superposed relation.

2. A foldable slat-type awning, comprising a fixed support secured in position adjacent to a frame opening, a series of slats, each having a tail piece extending transversely therefrom, a pantograph support for said slats comprising a series of crossed pivotally connected links to form an extensible and contractible lazy tongs, the terminal ends of two adjoining substantially parallel links at one end of said lazy tongs being pivotally mounted in spaced relation to said fixed support, the pivoted ends of said links at one side of said lazy tongs being pivotally connected to respective ones of said tail pieces, and a plurality of link members respectively pivotally connected at one end to the aforesaid pivotal connections between the slat tail pieces and lazy tongs, and at their opposite ends to adjoining tail pieces, whereby said slats are rotatable in opposite directions on their pivotal connection to said lazy tongs respectively by extension and contraction of the latter, movement of said lazy tongs to extended position from said fixed support extending said slats to transversely substantially edge-to-edge relation, and movement of said lazy tongs to contracted position towards said fixed support collapsing said slats into substantially parallel superposed relation.

3. A foldable slat-type awning, comprising a series of slats, each having a tail piece extending transversely therefrom, a fixed elongated trackway, a pantograph support for said slats comprising a series of crossed pivotally connected links to form an extensible and contractible lazy tongs, the pivoted ends of said links at one side of said lazy tongs being pivotally connected to respective ones of said tail pieces and each of said pivoted ends having a guide member slidably fitting in said trackway to cause said lazy tongs to extend and contract in line with said trackway, and a plurality of link members respectively pivotally connected at one end to the aforesaid pivotal connections between the slat tail pieces and lazy tongs, and at their opposite ends to adjoining tail pieces, whereby said slats are rotatable in opposite directions on their pivotal connection to said lazy tongs respectively by extension and contraction of the latter, movement of said lazy tongs to extended position extending said slats to transversely substantially edge-to-edge relation, and movement of said lazy tongs to contracted position collapsing said slats into substantially parallel superposed relation.

4. A foldable slat-type awning, comprising a fixed support secured in position adjacent to a frame opening, an uppermost slat and a series of additional slats, each of the slats having a tail piece extending transversely therefrom, the tail piece of said uppermost slat being pivotally connected to said support, a pantograph support for said additional slats comprising a series of crossed pivotally connected links to form an extensible and contractible lazy tongs, the terminal ends of two adjoining substantially parallel links at one end of said lazy tongs being pivotally mounted in spaced relation to said fixed support, a link pivotally connected between the tail piece of said uppermost slat and one of said parallel links, the pivoted ends of said crossed links at one side of said lazy tongs being pivotally connected to respective ones of the tail pieces, on said additional links, and a plurality of link members respec-

tively pivotally connected at one end to the aforesaid pivotal connections between the additional slat tail pieces and lazy tongs, and at their opposite ends to adjoining tail pieces, whereby all of said slats are rotatable in opposite directions on their pivotal connection respectively by extension and contraction of said lazy tongs, movement of said lazy tongs to extended position from said fixed support extending all of said slats to transversely substantially edge-to-edge relation, and movement of said lazy tongs to contracted position towards said fixed support collapsing all of said slats into substantially parallel superposed relation.

5. A foldable slat-type awning, comprising a series of slats each having laterally off-set portions at its longitudinal edges and each having a tail piece extending transversely therefrom, a pantograph support for said slats comprising a series of crossed pivotally connected links to form an extensible and contractible lazy tongs, the pivoted ends of said links at one side of said lazy tongs being pivotally connected to respective ones of said tail pieces, and a plurality of link members respectively pivotally connected at one end to the aforesaid pivotal connections between the slat tail pieces and lazy tongs, and at their opposite ends to adjoining tail pieces, whereby said slats are rotatable in opposite directions on their pivotal connection to said lazy tongs respectively by extension and contraction of the latter, movement of said lazy tongs to extended position extending said slats to transversely substantially edge-to-edge relation with the off-set portion of one interengaging with the off-set portion of an adjoining slat to limit extension of said lazy tongs, and movement of said lazy tongs to contracted position collapsing said slats into substantially parallel superposed relation.

6. In an awning structure comprising a plurality of slats having means for moving the same to adjusted positions, said slats each having transversely bent longitudinal edges extending in opposite directions, the combination of a strap overlying one surface of said slat and having a recessed portion slidably receiving one of the transversely bent edges of said slat, and a second strap transversely overlying the opposite surface of said slat and having a recessed portion slidably receiving the other transversely bent slat edge, and means for releasably connecting adjacent end portions of said straps together at the opposite longitudinal edge portions of said slat, whereby said slat may be clamped between said straps at various positions longitudinally of the slat.

7. In an awning structure comprising a plurality of slats having means for supporting them adjacent to a window or door opening, said slats each having transversely bent longitudinal edges extending in opposite directions, the combination of a strap overlying one surface of said slat and having a recessed portion slidably receiving one of the transversely bent edges of said slat, and a second strap transversely overlying the opposite surface of said slat and having a recessed portion slidably receiving the other transversely bent slat edge, said slats having interconnecting portions for releasably connecting adjacent end portions thereof together at one longitudinal edge portion of said slat, and releasable securing means for releasably connecting opposite adjacent end portions of said straps at the opposite longitudinal edge portion of said slat, whereby said slat may

be clamped between said straps at various positions longitudinally of the slat.

8. An awning structure comprising a pair of supports secured to opposite sides of a window or door opening, each having an arm extending laterally and outwardly from a respective side of said opening and each having a recess in its under surface, said recesses being generally aligned with each other, a slat extending cross-wise over said arms and having a pair of depending apertured tabs, the apertures in said tabs being generally axially aligned with each other and generally aligned with the recesses in said arms when said slat is positioned on said arms, and a cross rod extending through the apertures in said tabs

5 and seating within said recesses for holding said slat assembled with said supports and against movement longitudinally along said arms.

JONATHAN W. KING, JR.
